UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

MANIFOLDING SHEET

Original application filed September 5, 1922, Serial No. 586,064, now Patent No. 1,562,524, dated November 24, 1925. Divided and this application filed July 14, 1925. Serial No. 43,498.

This invention relates generally to printed forms and more particularly to a combined set of manifolding sheets and paper-webs.

Multiple - ply paper - webs, are sometimes 5 separate but more generally have their side edges connected in the form of a fan-fold web; a suitable variety of forms being printed upon the plies, and each form being torn off after typing, as set forth in the Wernery and

10 Smith Patent No. 1,132,055, dated March 16, 1915.

In some cases one of the duplicate forms is in the nature of an order-blank, which, when typed, is placed in the hands of the person 15 who collects the goods and delivers them to the shipping room. A single order sometimes covers a great variety of goods, and it is necessary that the order be split up and the different items thereof sent to different departments for execution. Each item occupies only 20 a single line of typing, and it has been found impracticable to type these split orders at the same time that the original is typed upon the fan-fold form. This is because there must 25 be typed upon a single fan-fold form a complete schedule of the items, whereas usually there must be typed upon each of the split-up orders only a single item. One of the objects 30 of this invention is to overcome this difficulty and enable the individual orders to be typed upon appropriate forms simultaneously with typing of the composite order upon the mani-fold forms.

For the orders, a sheet is provided having a 35 series of transverse perforated lines dividing the sheet or slip into sections or coupons adapted to be torn apart. A single item, composing a part of the order, is ordinarily written on each of these sections, so that the successive items on the sectional order-sheet or 40 slip appear with considerable space intervening between them. The same items appear on the bill, however, in closely spaced relation. This may be done in a machine of the type 45 referred to, whereby the bill-forms and the sectional order-sheets may be positioned and fed with relation to each other with a degree of facility and accuracy which will make it practically possible to typewrite both of them 50 at a single operation, notwithstanding the

great difference in the line-spacing of the same items on the bill and order-sheet or slip. In using a machine of this type, the leading edges of the main work-webs are withdrawn from between the platen and the feed-rollers 55 after the completion of each bill, and lifted up to permit the insertion beneath the main webs of a set of sectional order-sheets and carbon-sheets, so that these sectional order-sheets or slips will be presented to the types 60 outside of the main webs on the platen, that is, in a position where the slips may be grasped and adjusted upwardly by the operator, and where the outer slip will be visible 65 to the operator.

As above pointed out, the items are differently spaced on the bills and on the sectional order-sheets. In order that they may be written simultaneously, therefore, it is necessary that the bill webs and the sectional order-sheets be advanced different distances 70 between the typing of successive items. The bill is advanced by the usual line-spacing mechanism of the typewriter.

Another difficulty has arisen because, in splitting up the order, it has been the practice to typewrite the customer's address upon each section of the split-up order, although it is not desirable that such address should be repeated for each item upon the fan-fold 75 form, which should contain all of the items and only one address. This difficulty is also sought to be overcome by the present invention. To this end the address of the customer is printed upon the first of the sectional 80 forms or coupons, which may have a blank heading space for the purpose, and the same address, of course, will appear upon all of the fan-fold plies. The address is not repeated, and does not appear upon any of the remaining item forms or coupons. To serve the 85 same purpose as the address, however, a certain office number is printed or stamped upon the separate item forms or coupons, using the same number for each set of forms. The item forms are then distributed to various 90 departments, and as the orders are filled they are forwarded to the shipping department, which makes up the package to contain all 95 100

of the goods gathered under a given office number for shipping to that customer.

This is a division of my application, Serial No. 586,064, filed September 5, 1922 (now 5 Patent No. 1,562,524, dated Nov. 24, 1925.)

Other features and advantages will hereinafter appear.

In the accompanying drawings,

Figure 1 is a portion of a bill web adapted 10 to be used in a fan-fold machine.

Figure 2 is a sectional order-sheet to be typed simultaneously with the bill web of Figure 1.

Continuous forms or webs 10 are used in a 15 typewriting machine, such as shown in said patent to Wernery and Smith, No. 1,132,055.

In some cases, one of the duplicate forms is in the nature of an order-blank, which, when typed, is placed in the hands of the person 20 who collects the goods and delivers them to the shipping room. A single order sometimes covers a great variety of goods, and it is necessary that the order be split up into individual items and the different items sent 25 to their respective departments for execution. For this purpose there are provided sectional order forms or coupons 11 preferably printed upon webs or slips 12 and separated by perforated lines 13 for convenience 30 in tearing them off. These sectional order slips 12 may be narrower than the fan-fold webs 10 and may be collated properly relatively to the fan-fold webs by providing upon the typewriting machine a pocket in rear of 35 the platen. The order slip 12 may be advanced independently of the main work-web 10 to bring the leading section or coupon on the slip into register with the corresponding form of the main web, and then all the sheets 40 may be typed. Then the line-spacing mechanism is operated, and subsequently the sectional order slip 12 is independently advanced to bring the next order form or coupon 11 thereon into position in order to receive the 45 succeeding item, that is, the item which is to fall on the next line of typing on the fan-fold web. The typewriting machine is again line-spaced, and the sectional order web 12 is also advanced to bring the third form or coupon 50 11 thereon into typing position, and so on, so that the entire sectional order web may be typed during the typing of a single form on the fan-fold web. The sectional order forms or coupons may then be torn apart and distributed for execution, while the typed forms 55 may be torn off from the fan-fold web and the various plies thereof separated and distributed to the various billing, bookkeeping, shipping and other departments for the usual 60 purposes.

The bill-webs 10 and the sectional order slip 12 are typed simultaneously in the typewriting machine in the following manner: The carbon-sheets upon the carbon-holder are 65 interleaved with the several bill webs 10; sec-

tional order-sheets 12 are then selected, having as many sections or coupons 11 as there are items in the order, or preferably a complete set of coupons forming a sheet as prepared by the printer is used, and, if more than one sectional order-sheet of coupons is to be used, carbon-sheets are interleaved with them before they are presented to the machine. The platen being in its swung-up position, the ends of the bill webs 10 are then raised, and the sectional order-sheets 12, with their carbon-sheets, are thrust backwardly into the mouth of the pocket between the walls and gages. The leading edges of the main or bill webs 10 and the sectional order-sheets 12 are then aligned and inserted around the raised platen, which is then lowered to normal position. The operator then types the index number 14 of the order (which is obtained from the split-order slip and is there 70 printed on the heading and each section 11 or coupon of the sectional order-sheet 12), so that the bill 10 may be identified with the sectional order-sheet 12. The index number is copied on the heading adjacent the printed 75 index to serve as a check on the order. He then types the address 15 and the first item 16 on the list, line-spacing in the usual manner. When the first item has been written 80 and the operator has line-spaced the platen one space, clamps mounted on a front paper-table are moved to their active positions to grip and hold stationary the bill webs, which are ordinarily wider than the sectional order-sheets. The platen is then unlatched and 85 raised slightly to a position, wherein the paper will be released from the influence of the feed-rollers. The sectional order-sheet or slip 12 is then drawn forward independently of the main work-web 10 until the second section or coupon of the slip is in position to receive the second item 17. The platen 90 is then restored to its normal lowered or printing position, and the clamps are moved to release the bill webs 10 for line-feeding. A paper-knife may conveniently be used as a 95 gage in conjunction with the perforated lines 13 for determining the position of the sectional order-sheet 12 at each adjustment 100 thereof. This adjusting of the order-sheet 110 or slip is repeated after each item until all of the items have been typed. The platen is then raised, the sectional order-sheet is removed, and the coupons are detached from 115 each other to be distributed among the several departments, or, in case an entire sheet of forms is used and the individual items do not cover all the sections thereof, the coupons may be detached, beginning with the top one, and each down to the last section upon which 120 an item of the order is typed. On this last typed section, the remaining untyped sections will be left attached, and the group of 125 sections used as a single order-coupon. In this way, a check may be made upon the number 130

ber of items of the order when the various parcels of the order are collected for shipment, since, in case, as shown, the sheet contains seven sectional parts, when all seven of the parts are received with the parcels at the shipping department, it will be known that the complete order has been received for shipment. In this way, an order, of say four items, is typed upon the first four sections of the sheet and the sheet may be divided into order-coupons, the first three sections being detached as three order-coupons and the last four sections with the single item constituting the fourth coupon of the order. Thus, it will readily be seen that when the coupon with three untyped sections is received by the shipping department, the order includes parcels from four departments and that the order is not complete until the parcels with the other three coupons have been received. The bill webs 10 are then drawn forward until they come into contact with the gaging finger, and the carbon-holder is thrust rearwardly to withdraw the carbon-sheets from between the portions of the bill webs which have just been written upon, and position them for writing the succeeding bill. The platen is then lowered to grip the bill webs, and the portions which have been written upon are torn off by use of the knife. The platen is then raised a second time, the bill webs are withdrawn to permit the insertion of a second set of sectional order-sheets or coupons, and the entire cycle is repeated.

It will be understood, of course, that several items affecting a single department may, if desired, be typed on the same sectional order-sheet or coupon.

Variations may be resorted to within the scope of the invention, and portions of the improvements may be used without others.

Having thus described my invention, I claim:

1. A collocation of sheets for type-manifesting both a bill of many items and a set of order-distributors and parcel-collectors, said collocation including a relatively short bill-blank and a relatively long set of coupons, said bill-blank printed with appropriately designated columns for the entry of items thereon, said coupons joined to one another by weakened lines and forming a sheet, said coupons and said bill being appropriately identified by the same number upon each thereof, and said bill and said coupon-sheet appropriately printed with similar account-identifying headings and data, the height of each coupon being of many times the pitch of the line-spacing upon the bill, and being sufficiently ample to enable the coupon to be usable as a ticket for use in making up and then accompanying the parcel to which it belongs, to serve as an identifying slip thereon, said bill having sufficient length to accommodate as many ordinarily typed item-lines

thereon as there are coupons in the coupon-sheet, and said bill and coupon sheets being disjoined to permit advance of the coupon-sheet for the length of a coupon independently of the bill after the typing of each line, 70 said coupon-sheet having a top extension upon which its said heading is printed, said extension serving as a hand-hold to permit the sheet to be grasped thereby to advance it independently of the bill-sheet to effect wide spacing on the coupon-sheet of lines manifolded with ordinary spacing upon the bill-sheet.

2. A sheet for use in type-manifesting both a bill of many items and a set of order-distributors and parcel-collectors, said sheet consisting of a long set of coupons joined to one another by weakened lines, and being appropriately identified by the same number upon each thereof to agree with the number on the bill, said coupon-sheet appropriately printed with account-identifying headings and data to agree with the heading on the bill, the height of each coupon being of many times the pitch of the line-spacing usually employed upon a bill, and being sufficiently ample to enable the coupon to be usable as a ticket for use in making up and then accompanying the parcel to which it belongs, 85 to serve as an identifying slip thereon, said coupon-sheet having a top extension upon which its said heading is printed, said extension serving as a hand-hold to permit the sheet to be grasped thereby to advance it independently of the bill-sheet to effect wide spacing on the coupon-sheet of lines manifolded with ordinary spacing upon the bill-sheet.
